UNITED STATES PATENT OFFICE.

WILLIAM H. MAGEE, OF MOUNDSVILLE, WEST VIRGINIA, ASSIGNOR TO FOSTORIA GLASS COMPANY, OF MOUNDSVILLE, WEST VIRGINIA, A CORPORATION OF WEST VIRGINIA.

DESIGN FOR A BOWL.

Application filed February 18, 1927. Serial No. 20,805. Term of patent 14 years.

To all whom it may concern:

Be it known that I, WILLIAM H. MAGEE, a citizen of the United States, residing at Moundsville, in the county of Marshall and State of West Virginia, have invented a new, original, and ornamental Design for a Bowl, of which the following is a specification, reference being had to the accompanying drawing, forming part thereof.

Figure 1 is a perspective view; and

Figure 2 is a partial vertical sectional view; showing my new design.

I claim:

The ornamental design for a bowl as shown.

WILLIAM H. MAGEE.
